UNITED STATES PATENT OFFICE.

JOHN L. LIND, OF BAUDETTE, MINNESOTA.

BOWLING-ALLEY.

1,287,364.

Specification of Letters Patent. Patented Dec. 10, 1918.

Application filed February 1, 1918. Serial No. 214,921.

To all whom it may concern:

Be it known that I, JOHN L. LIND, a citizen of the United States, residing at Baudette, in the county of Beltrami and State 5 of Minnesota, have invented certain new and useful Improvements in Bowling-Alleys; and I do declare the following to be a full, clear, and exact description of the invention, such as will enable others skilled in the art 10 to which it appertains to make and use the same.

This invention relates to bowling alleys and it relates more particularly to an improved pin-centering device.

15 One of the objects of this invention is to provide an improved means for centering each bowling pin of a set automatically and with greater facility than has heretofore been accomplished.

20 Another object of the invention is to provide for quickly, efficiently and properly centering the bowling pins without the necessity of modifying the pins of ordinary construction.

25 Another object is to provide a device of this character in which the bowling pin seats are removable and interchangeable.

Another object is to provide a device of 30 this character which is comparatively simple of construction, comparatively inexpensive, and useful, practical and effective for the purpose indicated.

Other objects of the invention may become apparent to persons who read the following details of description in connection 35 with the accompanying drawings, in which:—

Figure 1 is a top plan view of a portion of a bowling alley constructed in accordance with one embodiment of the present invention;

Fig. 2 is a vertical sectional view taken along the line 2—2 of Fig. 1;

Fig. 3 is a vertical sectional view taken along the line 3—3 of Fig. 1;

45 Fig. 4 is an enlarged vertical sectional view taken along the line 4—4 of Fig. 1;

Fig. 5 is a horizontal sectional view taken along the line 5—5 of Fig. 4;

50 Fig. 6 is a perspective view illustrating one of the base blocks or bowling pin seats; and,

55 Fig. 7 is a perspective view illustrating a portion of the bowling alley in which one of the pin-centering sets of tapering guides is located.

Referring to these drawings in detail, in

which similar reference characters correspond with similar parts throughout the several views, the alley floor 10 is apertured at 11, the aperture preferably being cylindrical as illustrated in Fig. 5. Each aperture 11 is provided with any desired number of radial and axially extending recesses or slots 12 in each of which is secured a tapering or upwardly converging block or guide 13. However, these guides 13 are tapered only from a portion somewhat below the vertical center of the top, the lower portion having vertical sides and edges. The taper of the blocks 13 is such that their inner edges 14 conform to the lower end portion of a vertical bowling pin, so that such lower end portion enters the aperture 11 and is supported by the blocks 13 of its set, whereby the bowling pin is held in a position concentric with the cylindrical aperture 11. It will be seen, therefore, that by arranging the apertures 11 in the relative positions illustrated in Fig. 1, the bowling pins, when placed in the respective apertures 11, are positioned in proper relation to one another for bowling. As regards their vertical centers, however, it now becomes necessary to raise the bowling pins with their bases in registry with the top surface of the alley 10.

55 In order to quickly and simultaneously effect the raising of the bowling pins without shifting them laterally, I provide a series or set of bases or blocks such as illustrated in Figs. 4 and 6, and such bases are 60 preferably constructed and assembled as shown in these figures, although my invention is not limited to this exact construction. Referring especially to Fig. 4, I preferably provide a pedestal 14 of cast iron, internally 65 and concentrically screw threaded at its top and bottom, having its top and bottom surfaces in parallel planes, and having an apertured flange at its top. Upon the pedestal 14 I secure a block of wood, fiber, rubber or other somewhat yielding material; this member 15 being recessed centrally at 70 its top for receiving a plate or pin seat 16 of metal or other comparatively indestructible material. To the lower surface of the plate 16 is secured a screw 17 having its threads engaged with those formed in the upper end of the pedestal 14. The pedestal 14 and member 15 are provided with registering vertical slots 18 in which the guides 13 are seated.

75 There are as many of the devices shown

in Fig. 6 as there are apertures 11, and one of these members is arranged to move vertically in each of said apertures 11. In order to effect such arrangement and operation of the base members, I provide a platform 19, and I secure each of the base members to said platform by means of a screw or bolt 20, as illustrated in Fig. 4. It will be seen, therefore, that each of the base members or lifters will be raised by raising the platform 19.

In order that all parts of the platform may be raised and lowered to an equal extent, I preferably provide a plurality of 15 shafts 21, rotatable in bearings 22; and on each of these shafts I secure a spur gear wheel 23. These wheels are rotatable by means of a rack 24 which is adapted to be shifted longitudinally by a link 25 pivotally 20 connected thereto at 26. The link, in turn, is pivotally connected at 27 to a lever 28 having its fulcrum at 29. Rearward of the alley 10, I provide a hand lever 30, having its fulcrum at 31, and being pivotally connected to the lever 28 by means of a link 32. It will be seen, therefore, that the handle 30 is in a convenient position for operation by the setter-up of the bowling pins, and that by moving the lever 30 in one 30 direction, he shifts the rack 24 in one or the other direction. Suitable guides may be provided for the rack as indicated at 33.

On one of the shafts 21 is secured a single cam wheel or eccentric 34, while two of 35 such cam wheels or eccentrics 34 are carried by the other of the shafts, these three cam wheels being arranged in triangular relation to one another, because of the triangular arrangement of the bases or lifters. 40 When the rack 24 is moved in one direction the cam wheels 34 raise the platform 19, and when it is moved in the opposite direction, the cam wheels allow the platform to descend by gravity. Rollers 35 may be employed for facilitating the ease of operation of the device, but these may be dispensed with when desirable.

In order to protect the rim of each aperture 11, I may provide them each with a 50 ring 36 which is inlaid as indicated in Figs. 2 and 7 and this ring may be of vulcanized rubber or other yielding material, so that the sides of the bowling pins will not be detrimentally affected by contact therewith.

55 The cam wheels 34 are each in the form of an eccentric, and it is a well known law of mechanics, that uniform rotary movement of an eccentric imparts accelerated-and-retarded reciprocating movement to an element actuated by its convexed surface.

From the foregoing, it will be seen that this device greatly facilitates the setting up of bowling pins, as it is only necessary for the pins to be tossed into the apertures 11 65 while the platform 19 is in its lower posi-

tion, and the pins are automatically centered. It will also be seen that while the pins are very quickly raised to their set position, the accelerated and retarded raising movement thereof precludes any probability of lateral shifting of the pins. 70

Although I have described this embodiment of my invention in minute detail, my invention is not limited to these exact details of construction and arrangement of 75 parts, but I am entitled to make such changes that do not constitute a departure from the inventive ideas herewith disclosed.

What I claim as my invention is:

1. A bowling alley comprising an apertured floor provided with upwardly diverging guide elements in each of the apertures thereof, cushioning means around the upper end of each of said apertures, and means movable in said apertures for permitting the 80 bowling pins to have their lower ends seated in said apertures and for raising said lower ends out of said apertures.

2. In a bowling alley, a floor provided with apertures therethrough, said apertures 90 being arranged according to the desired setting of the bowling pins and each provided with a plurality of radially and axially extending slots, guide members arranged in the slots of each of said apertures in such 95 relation as to conform with the lower end portion of an ordinary bowling pin when said lower end is in the respective aperture, and means movable in each of said apertures for contacting with the lower ends of the 100 bowling pins and raising said lower ends into registry with the top surface of said floor.

3. In a bowling alley, a floor provided with apertures, bowling pin guides arranged 105 and fixedly secured in each of said apertures, said guides having downwardly converging surfaces to conform to the shape of the lower tapering portion of the bowling pins, and a lifter for each of said apertures and 110 having its upper end vertically movable therein.

4. In a bowling alley, a floor provided with apertures, bowling pin guides arranged in each of said apertures, said guides being 115 constructed and arranged to conform to the shape of the lower end portion of the bowling pins, a lifter for each of said apertures and having its upper end movable therein, a platform on which all of the lifters are 120 seated, shafts extending horizontally under said platform, eccentrics on said shafts, and means for rotating said shafts simultaneously and thereby raising all parts of said platform equally whereby all of said lifters 125 are raised with an accelerated and retarded movement for raising the bowling pins thereon in the manner specified.

5. In a bowling alley, a combined seat and lifter comprising an integrally cast pedestal, 130

a block of yieldable material secured on said pedestal, a bowling pin seat of relatively indestructible material on said block, and means co-operative with said seat for securing said blocks to said pedestal, said means also securing said seat on said block.

6. In a bowling alley, an apertured floor, inwardly extending guides arranged in each aperture of said floor, the upper portion of each guide being divergent upwardly with relation to the corresponding portion of the adjacent guide, the lower portion of each guide being parallel with the lower portion of the adjacent guide, and a lifter provided 15 with slots for receiving said guides, said lifter being vertically movable in said aperture and being guided by said guides, the upper portions of said guides being effective for guiding a bowling pin to a position concentric with said lifter.

7. In a bowling alley, an apertured floor,

bowling pin guides in the apertures of said floor, a lifter for each of said apertures and vertically movable therein, a member on which each of said lifters is seated, a pair 25 of rotary shafts extending horizontally under said member, a gear wheel mounted to rotate with each of said shafts, means on each of said shafts for exerting power for lifting said member, a rack engaged with 30 said gear wheels, a hand lever, and means connecting said hand lever with said rack for causing the latter to rotate said gear wheels and shafts and thereby lifting all of said lifters simultaneously.

In testimony whereof I have hereunto set my hand in the presence of two subscribing witnesses.

JOHN L. LIND.
